ABSTRACT

A new and distinct cultivar of Chrysanthemum plant named Sulphur Reagan, bearing medium sized yellow blooms with a yellow-green center and performance of 24-28 days.

2 Drawing Sheets

1

This is a continuation of application Ser. No. 07/767,791, filed Sep. 30, 1991, now abandoned. The present application is related to the following copending application:

5

Application No.	Filing Date	Title
07/780,305	October 22, 1991	Reagan
07/780,237	October 22, 1991	Orange Reagan
08/088,104	July 8, 1993	Dark Reagan
08/101,275	August 2, 1993	Coral Reagan
08/088,107	July 8, 1993	White Reagan

08/101,278	August 2, 1993	Salmon Reagan

2

SUMMARY OF THE INVENTION

The present invention is a new and distinct variety of chrysanthemum of a medium sized bloom and yellow color.

10

BRIEF DESCRIPTION OF THE DRAWINGS

The present invention of a new and distinct variety of chrysanthemum is shown in the accompanying drawings, the color being as nearly true as possible with color photographs of this type.

FIG. 1 shows the full bloom of the new cultivar.

FIG. 2 shows various stages of bloom of the new cultivar.

15

FIG. 3 shows foliage and petiole of the new cultivar.

DESCRIPTION OF THE INVENTION

This new variety of chrysanthemum is of the botanical classification *Chrysanthemum morifolium*. When grown in the vicinity of Ter Aer, Holland, it has a response time of approximately 7½ weeks. This new variety produces medium sized yellow blooms with a green center having a 4 week performance (i.e., vase life of 24-28 days). This new variety of chrysanthemum has been found to retain its distinctive characteristics throughout successive propagations and may be planted under greenhouse conditions in Holland between weeks 50 and 35 (i.e., between December 1 and August 30).

BACKGROUND OF THE INVENTION

The present invention comprises a new and distinct cultivar of Chrysanthemum plant which is a naturally occurring sport of a chrysanthemum named Reagan, which in turn is a cross of unknown *Chrysanthemum morifolium* parents. The invention was discovered in a greenhouse of the assignee as a whole plant mutation by Martinus van der Jagt in 1990 at Paradisweg 84-86, Ter Aar, Holland.

The plant has been asexually reproduced by cuttings at the same location. The new cultivar has been found to retain all of its distinctive characteristics through successive propagations.

Plant 8,786

3

The following is a description of the plant and characteristics (color designations are from The R.H.S. Colour Chart) that distinguish it over related known varieties and its antecedents:

Botanical classification: *Chrysanthemum morifolium*.
Bud:

Size.—Medium (cross section ± 1.0 cm, height ± 0.7 cm).

Form.—Round and flat.

Outside color.—Yellow 10C.

Bloom:

Size.—Medium.

Fully expanded.—7-7½ cm.

Borne.—Upper portion, single flower per peduncle; 15 lower portion, plural flowers per peduncle.

Stems.—Strong, thick.

Form.—Single (Daisy).

Performance.—Very good 24-28 days (18°-20° C.)

Color:

Center of flower.—Immature: yellow green 151C; Mature: yellow green 154A.

Base of petals.—Yellow 6D.

Inside of petals.—Yellow 6D.

Reverse of petals.—Yellow 6D.

Outer petals.—Yellow 6D.

Tonality from a distance.—A yellow daisy with a fresh looking center having little or no pollen.

Discoloration.—None.

Pollen.—Yellow-orange 14A.

Petals:

Texture.—Upperside smooth, underside smooth.

Number.—24-30 (two rows).

Cross-section.—Flat, two keels.

Arrangement.—Imbricated.

Persistence.—Good. Petals keep straight or reflex somewhat at the edge at the end of blooming.

Fragrance.—Typical Chrysanthemum.

Reproductive organs:

Stamen.—Yellow, thick, 3 mm.

40

Disc diameter.—1.5 cm.

Pollen.—Appears at a late stage of blooming, yellow-orange in color.

Style.—Green, thick. Length: ± 5 mm.

Stigmas.—Yellow. Width: ± 1 mm.

45

Ovaries.—Enclosed in calyx.

Plant:

Form.—Spray mum meant for erect culture. Herbaceous.

Growth.—Strong.

50

Height.—100-125 cm.

Peduncle.—Near the top ± 14 cm, near the middle ± 24 cm, near the bottom ± 28 cm.

Internodes.—3 cm.

Flowering response.—7½ weeks.

55

Foliation:

Color.—Upperside green 137 A, Underside 137 C.

Size.—Length ± 12 cm, Width ± 9 cm.

Quantity.—22-28.

Shape.—Lobed, see photograph

60

Texture.—Upperside rough, Underside smooth slightly hirsute.

Ribs and veins.—Ribs well developed, veins not so developed.

Edge.—Crenated.

Distinguishing characteristics of the Chrysanthemums of the Reagan family are summarized below in

4

Tables IA and IB. Color designations therein are taken from The R.H.S. Colour Chart.
